UNITED STATES PATENT OFFICE

FLOYD L. MUSGROVE, OF SHENANDOAH, IOWA, ASSIGNOR TO THE COLONIAL CABIN CAMP CORPORATION, OF TOPEKA, KANSAS, A CORPORATION OF KANSAS

DESIGN FOR A TOURIST PARK ENTRANCE UNIT

Application filed October 30, 1929. Serial No. 33,222. Term of patent 3½ years.

To all whom it may concern:

Be it known that I, FLOYD L. MUSGROVE, a citizen of the United States, residing at Shenandoah, in the county of Page and State of Iowa, have invented a new, original, and ornamental Design for a Tourist Park Entrance Unit, of which the following is a specification, reference being had to the accompanying drawing, forming part thereof.

Fig. 1 is a front elevation of the tourist park entrance unit, showing my new design.

Fig. 2 is an end view of the same.

I claim:

The ornamental design for a tourist park entrance unit as shown.

FLOYD L. MUSGROVE.
